UNITED STATES PATENT OFFICE.

CLARENCE J. COBERLY, OF LOS ANGELES, CALIFORNIA, ASSIGNOR, BY MESNE ASSIGNMENTS, TO PUROX COMPANY, OF DENVER, COLORADO, A CORPORATION OF COLORADO.

METHOD AND APPARATUS FOR PREVENTING FLASHBACKS.

Application filed September 6, 1922. Serial No. 586,536.

My invention relates to the art of welding and cutting metal by the use of high temperature flames produced by the combustion of various gases with oxygen. In practice, either acetylene or hydrogen is usually employed as the combustible gas, but various other gases, such as Blau gas, Pintsch gas, water gas, butane and so forth may be used with a considerable degree of success. Oxygen in different states of purity or nitrous oxide are usually employed as the combustion supporting gas. Torches for mixing and burning said gases are in very general use at the present time, being used for welding and cutting steel and other metal. It is usual practice in welding to supply about one-half the O₂ required for complete combustion as pure O₂, the remainder being taken from the air surrounding the flame. In all such torches now in commercial use trouble is experienced by flash backs; that is, by a premature combustion inside the torch. Since the temperature of the flame is very high, and continued combustion inside the torch results in a rapid destruction to the torch and requires shutting off, cooling and re-lighting to again establish the proper flame at the tip.

It is an object of my invention to prevent flash backs in such torches with any gas combination which it may be desired to use.

Further objects and advantages will be evident hereinafter.

Referring to the drawing, which is for illustrative purposes only,

Fig. 1 is a cross section through one embodiment of my invention.

Figs. 2 and 3 are sections on a larger scale than Fig. 1 on planes represented by the lines 2-2 and 3-3 respectively of Fig. 1.

Because of the extremely explosive nature of mixtures of oxygen and acetylene, early experiments with oxy-acetylene welding apparatus had a great deal of difficulty in overcoming trouble due to flash-backs. These flash-backs not only injured the torch, but at times even extended into the gas lines and caused more or less serious explosions, causing much delay and difficulty in executing welds.

Early inventors of welding apparatus de-

pended upon the principle of the Davy safety lamp for preventing the flame from entering the gas line. Claude and Le Chatelier in France were among the first to suggest this form of flash-back prevention. Claude proposed to fill chambers in the gas line with porous substances which would permit the flow of gas therethrough, but which would absorb the heat of a flame so rapidly that the flame would be extinguished before passing through. Le Chatelier and others worked on the same principle but substituted small elongated orifices for the porous disc. These small orifices were in the form of small holes or annular chambers formed by plugs and sleeves with very small differences in diameter. According to Le Chatelier, the operation of these methods of flash-back prevention depends upon the lowering of the flame velocity by the absorption of heat to a point where the natural velocity of the gases, due to the difference in pressure in the gas line and the exit of the torch, exceed the velocity of the flame. Under these conditions, of course, the flame would be forced to travel out and would ignite at the exit orifice of the burner.

Such methods are based upon a sound principle and no doubt are of material benefit in overcoming this trouble. However, all of these forms of flash-back prevention offer considerable resistance to the flow of gases through the torch and hence require greater pressures on the gas supply lines than would otherwise be necessary to deliver the required volume of gas. This is of special significance in the case of burners of very large capacity, since the maximum pressure available in the case of acetylene is that delivered by the generator, or at the most, the pressure at which acetylene is susceptible to spontaneous decomposition, generally accepted to be a pressure in the neighborhood of thirty pounds per square inch.

The high resistance to flow produced by this method led later inventors to discontinue the use of small orifices or porous plugs and to substitute therefor many other means of which a considerable number are entirely inoperative. Several inventors specify the use of burners in which the

gases are mixed at a point in close proximity to the point of combustion so that the volume of mixed gas within the burner is extremely small and so that there are no unnecessary chambers or pockets in which gas can accumulate. This method is effective at least for a certain range of burner capacity, but has the objection that when the gases are mixed at a point near the tip 10 of the burner the time allowed for the thorough mixing of the gases is insufficient and hence serious difficulties in obtaining sound welds are encountered. In many cases the time allowed for the mixing of the gases is 15 an extremely small fraction of a second and no special means is provided to cause the gases to mix.

Others have sought to overcome the trouble by interposing check valves in one or 20 both of the gas lines or in the passage carrying the mixed gases and depending upon the force of the explosion within the interior of the burner to close the valves and hold them closed for a sufficient time for the 25 flame to extinguish. The use of a check valve within the passage of a burner which carries mixed gas is entirely inoperative since the velocity of flame propagation in 30 confined spaces is so extremely high that the action of a check valve is too sluggish to prevent the passage of a flame. Some manufacturers have sought to prevent flash-backs by using flames which issue from the tip at 35 extremely high velocity. This also is of some value in the prevention of flash-backs but at the same time gives a flame which is termed too "hard" and causes a blowing action on the metal which is detrimental to the production of sound welds.

40 It has for some time been an accepted fact that torches which have the oxygen delivered to them at a pressure in excess of the acetylene pressure are more susceptible to flash-back than those in which the pressures were nearly equal. The principle here involved is that the restriction of flow, which tends to cause flash-back, retards most 45 the flow of the gas which has the lower pressure. Therefore, by using acetylene at 50 a higher pressure than oxygen, a restriction of flow causes an excess of acetylene to be delivered to the flame which gives a flame of much lower rate of flame propagation and hence there is much less possibility of 55 the flame traveling back into the interior of the torch. Several torches are on the market which operate on this principle. The rate of flame depends, however, upon the dimensions of the space in which the gases 60 are confined, and it is possible to set up a high velocity flame known as a detonating wave which has a velocity many times the normal flame velocity when burning in air unrestricted. Some inventors who have interposed check valves or other devices in the 65

interior of the torch to stop the propagation of the flame have recognized the fact that regardless of the velocity of exit of the flame gases or the ratio of oxygen to combustible gas in the flame, it is impossible at times to prevent the flame from entering the interior of the torch and that hence a means must be there located to prevent the continued combustion in the interior of the torch. The use of acetylene at excess pressure decreases 70 the liability of the flame entering the interior of the torch, but does not prevent the continued propagation therein after the flame has once been established. It also has the practical drawback that the conditions 75 which tend to cause flash-back cause an excess of acetylene to be delivered to the flame and hence does not give a flame which is suitable for welding. Also for cutting metals with oxygen, it is desirable to supply the 80 oxygen at pressures materially higher than the acetylene pressure and hence a third hose is necessary with a separate pressure reducing means to supply low pressure oxygen to the flame. It has further been found 85 that exactly balanced pressures at the point of mixing is highly desirable from the standpoint of delivering a flame which will produce high quality welds. This necessitates a construction which will not give a 90 variation in gas ratio due to partial restriction of the tip and hence requires the use of exactly balanced pressures at the point of mixing.

95 Also the use of unbalanced pressures is 100 a hazard since an obstruction of the tip will cause a flow of the gas under the high pressure into the line at the lower pressure and hence will give an explosive mixture back of the normal point of mixing. 105

I have found that it is entirely impossible to prevent the flame from entering the interior of the torch with the gas mixing at a sufficient distance from the tip for 110 thorough mixing, and have devised a method which is not intended to prevent the flame from entering the interior of the torch but which will cause the flame to become extinguished in a short interval of time in case it does enter therein. This is 115 accomplished without the use of mechanical devices or porous material and depends entirely upon the proper proportions of the orifices and volumes of gases in the torch 120 and is applicable to any gas combination which it is desirable to burn. The method employed for this purpose may be illustrated by means of the diagrammatic torch shown in Fig. 1. Gases are supplied to the gas lines 5 and 6 at substantially equal 125 pressures regardless of the nature of density of the gases used. The flow of oxygen is controlled by means of orifice 13 and flow of acetylene by means of orifice 14. The gases are thoroughly mixed in passage 130

12 and leave the torch at orifice 11, where they are ignited and burned.

In case a condition is caused to exist wherein the flame is caused to burn back

5 into the interior of the torch, the velocity of combustion attains a very high value resulting in a high pressure being established in that portion of the torch between the point of mixing and the tip from which 10 the gases issue. This pressure is relieved by three means. First, by discharging the burned gases through the tip to the atmosphere. Second, by discharge of the burned gas back through the orifice 13 into the 15 oxygen tube. Third, by discharge of the burned gas back through the orifice 14 into the acetylene tube. It is obvious that this reverse flow of gases in the supply line will cause a shutting off of the combustible 20 and combustion supporting gases and hence it will extinguish the flame in the chamber 12. The interior surface of the torch is quite highly heated by this explosion, insufficient oxygen is available for complete 25 combustion, and carbon is deposited on the interior walls of the passages in the case of a hydrocarbon combustible gas. If the oxygen should be the first gas to enter the 30 chamber 12 after the flash-back this carbon may be of sufficiently high temperature to again ignite in the presence of oxygen and the flow of acetylene mixed with the oxygen which follows sets up a combustion within 35 the interior of the torch which can only be extinguished by shutting off the gases manually.

In the case of hydrogen as the combustible gas, the operation and result are the same except that carbon is not deposited 40 in the passage 12. I have found, however, that if the oxygen is the first gas to again enter the passage 12 after a flash-back that the flame is established within the torch and will continue to burn there until shut off. The reason that hydrogen operates the same as a hydrocarbon is probably due to the fact that the explosion which takes place within the passages of the torch heats the interior surface to a very high temperature for an extremely small interval of time and that hydrogen is more efficient than oxygen in cooling this surface because of the higher heat conductivity of the hydrogen. In the case of hydrogen, it is probable 50 that the shutting off of the flow of gases, as described above, would be operative to prevent the combustion in the interior of the torch even though oxygen were the first to re-enter the torch if the interval between the entrance of the oxygen and the following of the hydrogen were sufficient to permit sufficient cooling of the surface. However, I have found it desirable to have 60 the hydrogen re-enter the torch first and the rule laid down in this specification is ap-

plicable to hydrogen and oxygen as well as any combustible gas which it is desired to burn.

By proportioning the orifices of the mixer to suit the characteristics of the gases being used, the relative reverse flow of gases can be governed so that when the pressure in the chamber 12 again becomes normal due to the release of the burned gases through the orifice of the tip, the acetylene will be the first 70 to again enter the chamber 12. Therefore, any glowing carbon will be extinguished. The flow of oxygen follows that of the acetylene an instant later and the two issue from the tip in the normal manner. The flame will 75 then be reestablished on the outside providing there is some material adjacent of sufficiently high temperature to ignite the mixture. This is nearly always the case in 80 practical work since the temperature of the 85 metal is sufficient to reignite the gases.

In order to apply this method to the prevention of flash-back in cutting torches, in which it is necessary that oxygen be supplied to the torch under high pressure unless a separate supply line is used for the flame, it is necessary to provide sufficient volume in the oxygen line between 5 and 13 by throttling the valve 15 in which the 90 gas is at a pressure substantially equal to that of the acetylene in order that the reverse flow volume in the oxygen tube will be greater than that in the acetylene tube. In case the pressures in the supply lines 5 and 6 are substantially equal and the volume 95 of the tubes 7 and 8 are the same, then the degree of ease with which the gases are forced back into the tubes O and A respectively when an explosion occurs in passage 12 depends, among other things, upon 100 the restriction in passages 13 and 14. By proper proportioning of these orifices for the gas combination in use, the reverse flow through passage 13 can be made greater than the reverse flow through passage 14. I 105 have found that if orifice 13 is substantially the same diameter as the passage 9, that the reverse flow through 13 is greater than that through 14 when the ratio of the area at 13 to the area at 14 is greater than the ratio of 110 the square root of the density of the gas in 13 to the square root of the density of the gas in 14. The form of the passage 13 and 14 has some effect on the exact ratio required but the above ratio has been found to give good 115 results regardless of the nature of the combustible gas. In case it is desirable to supply oxygen to valve 15 at a pressure greater than that on the combustible gas at 6, the 120 passage 7 should have considerable volume and if possible should be greater than the volume of 8. If the volume of 7 is approximately equal to the volume of 12, good 125 results are obtained regardless of the pressure supplied to the gas lines. In order that 130

the reverse flow in both lines is not excessive, which would sometimes cause decomposition of gas in 8, in the case of acetylene, the passage 9 should be equal to or less than orifice 11.

In using orifices of widely different sizes at 11, it is sometimes desirable to vary the total volume of gas between 11 and 9, the desired volume being larger with the larger orifice at 11. This is accomplished by providing in each tip a supplemental chamber 16 to suit the orifice 11 which is arranged to be removed with the orifice when changing tips.

15 While I have used the word acetylene to designate the combustible gas, I wish it to be understood that hydrogen and various hydrocarbons are practically equivalent thereto and that the method of preventing 20 flash-backs disclosed is equally operative in any case, and that I do not wish to be limited to any particular gases, the terms oxygen and acetylene being used in the claims for the sake of clearness and not in any restrictive sense.

I claim as my invention:

1. In a torch for mixing oxygen and acetylene, the combination of: walls forming a mixing chamber; walls forming an oxygen inlet passage into said chamber; and walls forming an acetylene inlet passage into said chamber, said acetylene inlet passage having a cross sectional area related to that of said oxygen passage as the square root of the acetylene density is related to that of the oxygen density computed upon a standard of substantially equal pressure.

2. In a torch for mixing oxygen and acetylene, the combination of: walls forming a mixing chamber; walls forming an oxygen inlet passage into said chamber; walls forming an acetylene inlet passage into said chamber, said acetylene inlet passage having a cross sectional area related to that of said oxygen passage as the square root of the acetylene density is related to that of the oxygen density, computed upon a stand-

ard of substantially equal pressure; and an oxygen chamber having a volume substantially equal to that of said mixing chamber, said chambers being so proportioned to compensate for difference in pressure of the two gases.

3. In a torch for mixing oxygen and acetylene, the combination of: walls forming a mixing chamber; walls forming an oxygen inlet passage into said chamber; walls forming an acetylene inlet passage into said chamber, said acetylene inlet passage having a cross sectional area related to that of said oxygen passage as the square root of the acetylene density is related to that of the oxygen density computed upon a standard of substantially equal pressure; an oxygen chamber posterior of, and communicating with the oxygen passage; and an acetylene chamber posterior of and communicating with, said acetylene passage, the volume of said chambers being directly proportionate to the pressure of gas to be employed.

4. In a torch for mixing a combustion-supporting-gas having a known density and pressure with a combustible gas having a known density and pressure, the combination of: walls forming a mixing chamber; walls forming a combustion-supporting-gas inlet passage; and walls forming a combustible gas inlet passage into said chamber, said combustible gas inlet passage having a cross sectional area related to that of said combustion-supporting-gas passage as the square root of the combustible gas density is related to that of the combustion-supporting-gas density, this proportioning of passages being to insure entrance of the combustible gas into the mixing chamber prior to the entrance of the combustion-supporting-gas for preventing premature ignition in the mixing chamber.

In testimony whereof, I have hereunto set my hand at Los Angeles, California, this 1st day of September, 1922.

CLARENCE J. COBERLY.
